BOOT TREE OR THE LIKE

Ivor J. Allsop, Bellingham, Wash., assignor to Allsop Automatic Company, Bellingham, Wash.

Filed Apr. 26, 1965, Ser. No. 84,945

Term of patent 14 years

(Cl. D87—5)

FIG. 1 is a front perspective view of a boot tree or the like, showing my new design.

FIG. 2 is a top plan view thereof;

FIG. 3 is a rear elevational view thereof; and

FIG. 4 is a left-side elevational view thereof.

The side not shown is a mirror image of the structure illustrated in FIGURE 4.

I claim:

The ornamental design for boot tree or the like, as shown and described.
